UNITED STATES PATENT OFFICE.

NICHOLAS S. VEDDER AND FRANCIS RITCHIE, OF TROY, AND TOBIAS S. HEISTER, OF LANSINGBURG, ASSIGNORS TO NICHOLAS S. VEDDER, OF TROY, NEW YORK.

DESIGN FOR COOKING-STOVE.

Specification forming part of Design No. 8,026, dated January 26, 1875; application filed December 30, 1874.
 [Term of Patent 3½ years.]

CASE B.

To all whom it may concern:

Be it known that we, NICHOLAS S. VEDDER, of the city of Troy, in the county of Rensselaer and State of New York, FRANCIS RITCHIE, of the said city of Troy, and TOBIAS S. HEISTER, of the village of Lansingburg, in said county of Rensselaer, New York, have jointly invented and produced a new and original Ornamental Design for Cooking-Stoves, of which the following is a specification, reference being had to the accompanying cut, print, or engraving of a cooking-stove having our said new design.

One part of this invention consists of the design for the compound panel ornament A, composed of the octagonal molding-frame b, surrounding the swelling octagonal panel c, having the rosette d at its center, the angular standards e e, one on each side of the frame b, and enlarged toward their ends, and mounted over the upper angles of quadrilateral projecting base-blocks f f, which are connected by the bar g, having the ornament h beneath, and the tops of the said standards e e being under the scrolls i i, that extend upward to the cap ornament formed by the flowers k, leaves l, and crest m, all shaped, ornamented and combined so as to appear substantially as represented in the aforesaid cut, with or without the forwardly-projecting leaf and flower branches o.

Another part consists of the design for the oven-door, composed of the compound panel ornament A on the plain surface U, and the ornamental border P, all shaped and arranged together substantially as represented in the aforesaid engraving.

Another part consists of the design for the door or panel V at the end of the fire-box, composed of the compound ornament w, arranged on the plain surface x, and formed by an octagonal frame-molding, surrounding a swelling octagonal panel-surface having a central rosette, and with ornamental projections on the outer sides and top and bottom of the said frame-molding, and the ornamental border y, formed by the vine with leaves thereon, and the whole shaped in the several parts and arranged together so as to appear substantially as represented in the aforesaid print.

Another part consists of the design for the front door, composed of the oblong curved top tablet-panel Z, surrounded by the ornamental border a, formed by the vine with leaves and tendrils thereon, all shaped and arranged together substantially as shown in the aforesaid engraving.

Another part consists of the design for the leg B, composed of the compound ornament j, formed of the leaves, flowers, and grape-like cluster on the convex surface p, the molding v having an arch at top, and inclosing the surface p and the side scrolls z, all shaped and combined so as to appear as represented in the aforesaid cut.

What we claim as our joint invention is—

1. The design for the compound panel ornament A, composed of the molding-frame b, panel c, rosette d, standards e e, base-blocks f f, bar g, ornament h, scrolls i i, flowers k, leaves l, and crest m, all shaped, ornamented, and arranged together substantially as specified and shown.

2. The design for the oven-door, composed of the compound ornament A on the panel U, and the ornamental border P, all shaped and arranged together as set forth.

3. The design for the door or panel V, composed of the compound ornament w, panel x, and border y, formed by the vine and leaves, all shaped and arranged together as shown and described.

4. The design for the front door, composed of the tablet-panel Z, and the surrounding ornamental border a, formed by the vine with leaves and tendrils thereon, arranged on the narrow extended surface, and the whole shaped and arranged together as shown in the aforesaid cut or engraving.

5. The design for the leg B, composed of the compound ornament j, surface p, surrounding molding v, and side scrolls z, all shaped and arranged as shown and specified.

In testimony whereof we hereunto subscribe our names this 24th day of December, 1874.

NICHOLAS S. VEDDER.
 FRANCIS RITCHIE.
 TOBIAS S. HEISTER.
